UNITED STATES PATENT OFFICE.

ADIEL Y. DODGE, OF SOUTH BEND, INDIANA, ASSIGNOR TO BENDIX BRAKE COMPANY,
OF CHICAGO, ILLINOIS, A CORPORATION OF ILLINOIS.

BRAKE SHOE.

Application filed December 17, 1925. Serial No. 75,905.

This invention relates to brake shoes, and is illustrated as embodied in a sheet-metal central shoe for a three-shoe automobile brake. An object of the invention is to provide a shoe particularly adapted for use in a brake of this general character, different arrangements relating to constructing an anchoring arm at one end of the shoe arranged to overlap an adjacent shoe, to forming the opposite end for attachment to a floating or servo shoe, and to important improved details in building the shoe up from sheet metal stampings.

These various features of novelty will be apparent from the following description of the illustrative embodiment shown in the accompanying drawings, in which:

Fig. 1 is a vertical section through the brake, just inside the wheel, showing the shoes in side elevation;

Fig. 2 is an inside elevation of the novel center shoe;

Fig. 3 is a side elevation of this shoe detached;

Fig. 4 is a section through this shoe on the line 4-4 of Fig. 1;

Fig. 5 is a section through this shoe on the line 5-5 of Fig. 1, showing its anchor pivot; and

Fig. 6 is a partial section through two of the shoes on the lines 6-6 of Fig. 1, showing the articulating pivot connecting them.

The brake illustrated includes a drum 10 and a backing plate 12. A double cam 14 expands against the resistance of a main return spring 16 a reverse shoe 18 anchored to plate 12 at 20, and a floating or servo shoe 22. Shoe 22 turns with the drum and forces against the drum a center shoe 24 anchored at 26, against the resistance of an auxiliary return spring 28.

Each of the shoes 18 and 22 is forked or otherwise formed at its end to straddle or otherwise overlap its end of the center shoe 24. While no particular manner of forming these shoes is essential to the present invention, they may if desired be made as described and claimed in either of my copending applications Nos. 24,426 and 64,535, filed respectively April 20, 1925, and October 24, 1925.

The present invention relates more particularly to the shoe 24. It is apparent that at its anchored end it is offset inwardly of the cylindrical curve of the friction face

of the shoe, and extends between the arms forming the forked end of shoe 18. This permits the friction face of shoe 18 to be brought very close to the end of the friction face of shoe 24.

Preferably shoe 24 is made up of two angle-section stampings riveted or otherwise secured back to back, as appears in Figs. 4, 5, and 6. A flange 30 extends continuously around each of the stampings, a part of the two flanges 30 being cylindrical and together forming the friction face of the shoe, the brake lining 32 being secured to this face. The flanges 30, where offset inwardly of the curve of the friction face of the shoe at its anchored end, are narrowed so that they fit within the arms forming the overlapping end of shoe 18, the fit being loose enough to facilitate assembly of the brake, but at the same time close enough to position the shoe 18 laterally.

Anchor pivot 28 extends through relatively large openings 34 in the arms of shoe 18, so that it does not interfere with the movement of that shoe, and similarly anchor pivot 26 of shoe 18 extends through a relatively large opening 36 in the central web of shoe 24. The material of the parts of the two stampings forming the central web of shoe 24 is displaced in opposite directions about the opening 38 through which pivot 28 passes, to form a triangular lubricant-retaining groove 40 surrounding the pivot.

At its opposite end, shoe 24 comes to a blunt point, to avoid interference with shoe 22, the central web being tapered down at the end of the shoe to give this form. Some distance from this end, the shoe is formed with an opening 42, having a lubricant-retaining groove 44, for an articulating pivot 46 connecting it to the arms forming the overlapping end of shoe 22 (Fig. 6). Pivot 46 has a smooth enlarged head 48 slidably engaging the backing plate 12 to position the shoe laterally. The flanges 30 of shoe 24, between opening 42 and the end of the shoe, are formed with short lugs or projections 50, serving as centering projections to engage the inside surfaces of the arms forming the end of shoe 22. Between opening 42 and projections 50 is a small opening 52, to provide for the attachment of spring 26.

While one particular shoe has been described in detail, it is not my intention to limit the scope of the invention to that pa-

ticular shoe, or otherwise than by the terms of the appended claims.

I claim:

1. A brake shoe having a substantially cylindrical friction face and a radial strengthening web extending a considerable distance beyond the friction face and offset within the curve of the friction face at one end of the shoe provided with a relatively large opening for the anchor of an adjacent shoe at a point within the angle determined by the friction face.
2. A brake shoe having a substantially cylindrical friction face and a radial strengthening web extending as an anchoring arm a considerable distance beyond the friction face at one end of the shoe and provided with a relatively large opening for the anchor of an adjacent shoe at a point within the angle determined by the friction face.
3. A brake shoe having a substantially cylindrical friction face and a radial strengthening web extending as an anchoring arm at one end of the shoe a considerable distance beyond the friction face, said web tapering down at the opposite end of the shoe to a blunt point at the opposite end of the friction face, to afford ample clearance for an adjacent shoe.
4. A brake shoe having a substantially cylindrical friction face and a radial strengthening web extending as an anchoring arm at one end of the shoe a considerable distance beyond the friction face, said web tapering down at the opposite end of the shoe to afford ample clearance for an adjacent shoe, said web having an opening some distance from said opposite end, to be pivotally connected to said adjacent shoe.
5. A brake shoe having a substantially cylindrical friction face and a radial strengthening web extending as an anchoring arm at one end of the shoe a considerable distance beyond the friction face, said web tapering down at the opposite end of the shoe to afford ample clearance for an adjacent shoe, said web having an opening some distance from said opposite end, to be pivotally connected to said adjacent shoe and having a second opening for attachment of a return spring between said first opening and said opposite end of the shoe.
6. A brake shoe having a substantially cylindrical friction face and a radial strengthening web extending as an anchoring arm at one end of the shoe a considerable distance beyond the friction face, said web tapering down at the opposite end of the shoe and adapted to be straddled by arms forming the end of an adjacent shoe, the web having laterally-extending centering lugs near said opposite end for engagement with the inner faces of said straddling arms.
7. A brake shoe including two angle-section stampings secured back to back, and having an opening for a pivot with the material of the stampings oppositely displaced about the opening to form a lubricant-retaining groove about said pivot.
8. A brake shoe including two angle-section stampings secured back to back, and having near each end an opening for a pivot with the material of the stampings oppositely displaced about each opening to form a lubricant-retaining groove about the corresponding pivot.
9. A brake shoe including two angle-section stampings secured back to back, with oppositely-extending lugs pressed from the inner edges of the webs of the stampings near one end of the shoe, to form centering projections to engage the inner faces of a pair of straddling arms forming the end of an adjacent shoe.
10. A brake shoe including two angle-section stampings secured back to back, with a flange extending continuously around the edge of the back of each stamping, part of each flange being cylindrical and forming half the friction face of the shoe, and the flanges being considerably narrowed in width and displaced within the curve of the cylindrical part for a considerable distance at one end of the shoe, to form a stiffened anchoring arm.

In testimony whereof, I have hereunto signed my name.

ADIEL Y. DODGE.
